(57) **CLAIM**

The ornamental design for picnic kit assembly, as shown and described.

DESCRIPTION

FIG. 1 is a top perspective view of a carrier tray portion, shown separated for ease of illustration, for a picnic kit assembly showing my design;

FIG. 2 is a front elevational view thereof, with the rear elevational view being a mirror image thereof;

FIG. 3 is a left elevational view thereof;

FIG. 4 is a right elevational view thereof;

FIG. 5 is a top plan view thereof;

FIG. 6 is a bottom plan view thereof;

FIG. 7 is a bottom perspective view thereof;

FIG. 8 is a cross sectional view thereof taken along line 8—8 of FIG. 5;

FIG. 9 is a top perspective view of a flatware holder portion, shown separated for ease of illustration, for a picnic kit assembly showing my new design;

FIG. 10 is a front elevational view thereof;

FIG. 11 is a rear elevational view thereof;

FIG. 12 is a left elevational view thereof;

FIG. 13 is a right elevational view thereof;

FIG. 14 is a top plan view thereof;

FIG. 15 is a bottom plan view thereof;

FIG. 16 is a bottom perspective view thereof;

FIG. 17 is a cross sectional view thereof taken along line 17—17 of FIG. 14;

FIG. 18 is another cross sectional view thereof taken along line 18—18 of FIG. 14; and,

FIG. 19 is a top perspective view of a picnic kit assembly shown in use condition.
